METHOD OF PREPARING APPLIQUÉS
FOR ATTACHMENT

Maurice A. Friedlen, Chicago, Ill.

Application September 13, 1946, Serial No. 696,904

5 Claims. (Cl. 2-278)

1

This invention relates generally to a method of attaching appliqués to surfaces of fabrics and the like and more particularly to a method of preparing the edges of appliqués to facilitate attachment to such surfaces.

Appliqués in the form of monograms, initials or ornamental designs have been attached to surfaces of fabrics by stitching along the marginal edges of the appliqués. When an appliqué is cut from felted materials, the cut edges thereof will not ravel and, consequently, such appliqués may be attached to surfaces without further work on the edges. When, however, an appliqué is cut from woven, knitted or similar fabrics, the cut edges of which are subject to ravelling, the edges of the appliqué must be bent under, before stitching, in order to present a smoothly defined outline of the particular configuration and also to prevent ravelling of the fabric along the cut edges thereof.

Heretofore, it had been the practice in attaching an appliqué made from woven or knitted materials to fold under and baste the cut edges thereof preliminary to stitching the same on a fabric surface. It is apparent that such an operation requires special skill and is time-consuming, thereby making appliqué work of this type relatively expensive and consequently limiting the field of commercial use to relatively high cost articles.

In accordance with the foregoing, it is, therefore, an object of my invention to provide a simple and efficient method of preparing the edges of appliqués for stitching, whereby basting of the edges preliminary to stitching is completely eliminated.

Another object of my invention is the provision of a method for preparing the edges of appliqués for stitching, which method requires no special skill and which may be readily performed to permit production on a quantity basis so as to materially reduce the cost of attaching appliqués to surfaces of fabrics or the like.

Other and further objects of the present invention will be apparent from the following description and claims and are illustrated in the accompanying drawings. Other embodiments of the invention embodying the same or equivalent principle may be used, and structural changes may be made as desired by those skilled in the art without departing from the present invention and the purview of the appended claims.

In the drawing:

Fig. 1 is a fragmentary plan view of an appliqué stitched to a surface of application and having a

2

portion broken away to show details of construction.

Fig. 2 is a perspective view of a die plate and pattern, in accordance with my invention, with the parts in spaced relation and showing, in broken lines, an appliqué blank in position for processing.

Fig. 3 is an enlarged fragmentary transverse cross-sectional view showing a step in my method of preparing the edges of an appliqué for attachment.

Fig. 4 is a similar view showing a subsequent step in my method of preparing the edges of an appliqué for attachment.

15 In practicing my invention I make use of a die plate 10 formed of any suitable material such as wood, metal or plastics. On a surface of the plate, I provide a shallow recess 11 formed of a desired configuration, such as that of a monogram, letter or an ornamental design. In the embodiment disclosed in the drawing, the recess 11 is shown, by way of illustration, in the form of the letter T. It will be understood, however, that the selection of the particular letter is solely for illustrative purposes and that it is intended that any desired configuration may be used.

For cooperation with the die plate 10 I provided a pattern 12 formed of thin sheet material preferably having some rigidity and cut to a configuration corresponding to the recess 11 in the die plate 10. The pattern 12 dimensionally is slightly smaller than the recess 11 and is intended to be received therein so as to leave a narrow marginal space along all edges, for reasons as will presently be made known.

35 In carrying out my invention, a blank 13 is first cut from fabric material to conform generally to the desired configuration, and recess 11, but has integral marginal extensions 14 to provide an oversized member. The blank 13 is then positioned over the die recess 11 centrally relative thereto so that the marginal extensions 14 of the blank extending over the edges of the recess 11 are substantially of uniform width. The pattern 12 is then superimposed over the fabric blank 13 and pressed into the recess 11. As a result the marginal extensions 14 of the blank 13 are caused to turn upwardly substantially at right angles to the plane of the body of the blank, as illustrated in Fig. 3. Thereafter, heat and pressure such as ordinarily secured by human force exerted on an ordinary flat-iron are applied to cause the marginal edges 14 of the blank 13 to fold inwardly and to lie flat against the pattern 12, as illustrated in Fig. 4. The depth of the

recess 11 preferably should be equivalent to the thickness of the pattern 12 plus two thicknesses of the fabric blank 13, such that when the marginal extensions 14 are folded over they will lie substantially in the same plane as the top surface of the die plate 10 and will permit a flat-iron 16 readily to pass thereover. After the marginal extensions 14 are pressed into position, as shown in Fig. 4, the pattern 12 is removed and the formed appliqué is then in condition for attachment to a surface, which attachment may be effected by stitching the appliqué along a marginal line 15, as shown in Fig. 1.

It will be apparent that in some cases it may be desirable to add body or rigidity to the finished appliqué. In that event, the pattern 12 may be formed from buckram or crinoline and retained in the folded marginal edges 14 when the appliqué is stitched to a surface.

I have found that when the pattern is formed from buckram the results are particularly satisfactory, since it appears that the fabrics of the appliqué blanks tend to adhere to a greater degree to the surface of the buckram than to patterns made from materials having smooth surfaces. Additionally, folded-under marginal edges of the appliqués tend better to retain their position for the final stitching operation when moisture or steam is used concurrently with the application of heat and pressure, in the pressing operation above described, and also when the same pressing operation is repeated on the appliqué after the pattern has been removed therefrom.

It will be seen from the foregoing that I have provided a method of preparing appliqués for attachment to a surface wherein the edges are very readily and accurately folded over and retained in that condition to form a configuration having a smoothly defined outline, and in condition for stitching to a surface of application.

I claim:

1. The method of preparing the edges of an appliqué for attachment to a surface comprising cutting a blank of the material to be applied, placing the said blank over a die recessed to conform to a desired configuration, with the marginal edges of the said blank extending over the edges of said recess, cutting a form from sheet material to a configuration corresponding to that of said recess but being relatively smaller dimensionally so as to be received in said recess, placing said form over said blank and urging said form and said blank into said recess so as to cause the marginal edges of said blank to be turned upwardly out of the plane thereof, applying heat and pressure to the upwardly turned, marginal edges to cause the same to be folded inwardly, and removing the said appliqué from said die.

2. The method of preparing the edges of an appliqué for attachment to a surface comprising cutting a blank of the material to be applied, placing the said blank over a die recessed to conform to a desired configuration, with the marginal edges of the said blank extending over the edges of said recess, cutting a form from sheet material to a configuration corresponding to that of said recess but being relatively smaller dimensionally so as to be received in said recess, placing said form

over said blank and urging said form and said blank into said recess so as to cause the marginal edges of said blank to be turned upwardly out of the plane thereof, applying heat and pressure to the upwardly turned marginal edges to cause the same to be folded inwardly, removing said appliqué from said die, and removing said form from said formed appliqué.

3. The method of forming and attaching an appliqué to a surface which comprises cutting a blank of the material to be applied, placing the said blank over a die recessed to conform to a desired configuration, with the marginal edges of the said blank extending over the edges of said recess, cutting a form from sheet material to a configuration corresponding to that of said recess but being relatively smaller dimensionally so as to be received in said recess, placing said form over said blank and urging said form and said blank into said recess so as to cause the marginal edges of said blank to be turned upwardly out of the plane thereof, applying heat and pressure to the upwardly turned marginal edges to cause the same to be folded inwardly, removing said appliqué from said die and stitching said appliqué to said surface.

4. The method of forming and attaching an appliqué to a surface which comprises cutting a blank of the material to be applied, placing the said blank over a die recessed to conform to a desired configuration, with the marginal edges of the said blank extending over the edges of said recess, cutting a form from sheet material to a configuration corresponding to that of said recess but being relatively smaller dimensionally so as to be received in said recess, placing said form over said blank and urging said form and said blank into said recess so as to cause the marginal edges of said blank to be turned upwardly out of the plane thereof, applying heat and pressure to the upwardly turned marginal edges to cause the same to be folded inwardly, removing said form from said formed appliqué, and stitching said appliqué to said surface.

5. The method of preparing edges of an appliqué for attachment to a surface comprising cutting a blank of the material to be applied, placing the said blank over a die having a recess conforming to a desired configuration with the marginal edges of said blank extending over the edges of said recess, placing a form conforming in configuration to said recess over said blank and pressing said form and said blank into said recess so as to cause the marginal edges of said blank to be turned upwardly out of the plane thereof, thereafter applying heat and pressure to said marginal edges to cause the same to be folded inwardly.
